CLAIM

The ornamental design for a display screen with animated graphical user interface, as shown and described.

DESCRIPTION

FIG. 1 is a front view of a first image of a display screen with animated graphical user interface;

FIG. 2 is a front view of a second image thereof;

FIG. 3 is a front view of a third image thereof; and,

FIG. 4 is a front view of a fourth image thereof.

The appearance of the image sequentially transitions between the images shown in FIGS. 1-4. The process or period in which one image transitions to another image forms no part of the claimed design.

The broken lines of uneven length show a screen for displaying the animated graphical user interface and form no part of the claimed design. The broken lines of even length shown in the drawing illustrate portions of the animated graphical user interface that form no part of the claimed design.

1 Claim, 4 Drawing Sheets
